(57) **CLAIM**

The ornamental design for an inhaler, as shown and described.

DESCRIPTION

FIG. 1 is a front-left isometric view of an inhaler showing our new design;

FIG. 2 is a rear-right isometric view thereof;

FIG. 3 is a front view thereof;

FIG. 4 is a rear view thereof;

FIG. 5 is a right side view thereof, the left side view being a mirror image of the right side view;

FIG. 6 is a top view thereof;

FIG. 7 is a bottom view thereof;

FIG. 8 is front-left isometric view thereof in a first open position;

FIG. 9 is a rear view thereof in the first open position;

FIG. 10 is a right side view thereof in the first open position, the left side view being a mirror image of the right side view;

FIG. 11 is a top view thereof in the first open position;

FIG. 12 is a rear-right isometric view thereof in the first open position;

FIG. 13 is a front-left isometric view thereof in a second open position;

FIG. 14 is a rear-left isometric view thereof in the second open position; and,

FIG. 15 is a right side view thereof in the second open position, the left side view being a mirror image of the right side view.

The broken line showing in FIG. 7 is for the purpose of illustrating a portion of the inhaler and forms no part of the claimed design.

1 Claim, 14 Drawing Sheets
